UNITED STATES PATENT OFFICE.

MICHAEL WOODS, OF CARLTON, AND THOMAS JEFFERSON GILBERT, OF BRUNSWICK,
VICTORIA, AUSTRALIA.

MACHINE FOR DRESSING RAILS.

1,032,722.

Specification of Letters Patent. Patented July 16, 1912.

Application filed February 4, 1911. Serial No. 606,498.

To all whom it may concern:

Be it known that we, MICHAEL WOODS, a subject of the King of Great Britain and Ireland, and residing at 309 Pigdon street,

5 Princes Hill, Carlton, in the county of Bourke, State of Victoria, Commonwealth of Australia, and THOMAS JEFFERSON GILBERT, a subject of the King of Great Britain and Ireland, and residing at 1 Minnie street, 10 Brunswick, in the county of Bourke, State of Victoria, Commonwealth of Australia, have invented certain new and useful Improvements in and Relating to Machines for Dressing Rails, of which the following is a 15 specification.

This invention relates to machines for dressing rails of the kind in which the dressing means are carried by an attachment which is pivotally secured to the machine as 20 described, for example, in the specification to our co-pending application Serial No. 538519.

The object of the present invention is to provide an efficient and readily attachable 25 combined carriage and holder for grinding means adapted for use in removing corrugations and to lengthen short joint depressions.

One mode of carrying out the invention is 30 illustrated by the accompanying drawings in which—

Figure 1 is an elevation of a combined carriage and holder constructed in accordance with the present invention. For clearness, parts have been sectioned, omitted or broken away. Fig. 2 is a plan of Fig. 1. For clearness parts have been sectioned, omitted or broken away. In this connection, portion of a grinding wheel guard has 40 been removed, portion of one grinding wheel broken away and part of the worm gear for raising and lowering the said wheel removed. Fig. 3 is an end elevation of Fig. 2, looking in the direction of a single arrow. Fig. 4 is an end elevation of Fig. 2 looking in the direction of the pair of arrows. One 45 grinding wheel and its dresser are removed, and a friction pinion at the opposite side is seen by the omission of an eccentric cylindrical bearing.

In carrying out the invention according 50 to one mode, the combined carriage and

holder consisting of a framework *a* is provided with holes for accommodating the hollow trunnions on the platform of the rail-dressing machine, which holes are covered by removable trunnion caps *j*, to allow of 60 the combined carriage and holder being removed when necessary. The framework *a* is supported on one side by a flanged wheel *b* mounted upon a pin *c* which is secured to or formed integral with a slide *d* which can be 65 adjusted in a vertical direction by means of a screw *e* upon which is a worm wheel *f* engaging with a worm *g* upon a shaft *h* which can be operated by means of a hand-wheel *i*. The other side of the framework *a* is supported upon a series of rollers *k* mounted 70 upon axles *l* turning within a carrier *m* which is formed in two parts joined together and is provided with a hole through which passes the outer end of a pin *n*, the 75 inner end *o* of which is secured to the framework. The carrier *m* is provided with inner and outer lugs *p* and *q* having pins upon which are mounted side rollers *r* and *s*, the outer rollers *s* being beveled so as to clear 80 upstanding fishplates. When grooved rails are to be operated upon, these side rollers are removed.

Mounted behind the rollers are the grinding wheels *t* and *u* which are driven, by any 85 suitable motor carried by the rail dressing machine, the arrangement of the gearing for transmitting the drive being as follows:—The shaft *v*, which passes through the hollow trunnions of the machine, is connected 90 at one end to a motor-driven shaft by a suitable coupling, and is provided at its other end with a bevel wheel *w* engaging with a bevel wheel *x* mounted upon a shaft *y* which carries a toothed wheel *z* which engages 95 with a toothed wheel 1 mounted upon a shaft 2. These toothed wheels are interchangeable with reserve wheels carried by the machine, so that a uniform peripheral speed may always be maintained for the 100 grinding wheels. The shaft 2 carries a friction wheel 3 engaging with friction wheels 4 mounted upon shafts 5 to each of which is secured one end of a suitable universal coupling 7 the other end of which is connected to a grinding wheel shaft 8 rotating within a bearing 9.

In order to start or stop either of the 105 grinding wheels each friction wheel 4 is mounted eccentrically within a cylindrical 110

bearing 6, to the ends of which are secured toothed wheels 10 which engage with toothed pinions 11 mounted upon a shaft 12 which also carries a spiral pinion 13 engaging with another spiral pinion 14 upon an inclined shaft 15. The shaft 15 carries at its upper end a bevel wheel 16 engaging with a bevel wheel 17 carried on a shaft 18, which can be operated by means of a hand wheel 19, which, on being turned, gives a partial rotation to the cylindrical bearing 6 thus moving the shaft 5 carrying the friction wheel 4 toward or away from the friction wheel 3. Each bearing 6 is provided with an elongated recess or recesses, engaging with a suitable stop or stops 20 projecting from the framework *a* thus limiting the movement of the bearing.

Each grinding wheel can be adjusted in a vertical direction by means of a hand wheel 22 which operates a shaft 23 provided with a worm 24 engaging with a worm wheel nut 25. Each wheel 25 rests upon a collar 27 pivoted in bearings on the framework and forms a nut around the screw 28 which is pivoted to lugs 29 of the bearing 9 from the inner end of which extend links 21 pivoted to the framework by means of a pin 30. On turning the hand wheel 22 the worm wheel nut 25 is caused to rotate, thus raising or lowering the screw 28 and consequently the grinding wheel shaft.

When the rails of a track do not correspond in lateral elevation, that is, when one is higher than the other, it is obvious that independently of the position of the machine, the combined carriage and holder, upon reaching such a part of the track, will turn slightly upon the trunnions, thus permitting deformities in one rail being treated independently of those in the other rail. In order to bring the grinding wheels into the same lateral plane as the surface of the rail which is being treated, the flanged wheel *b* is adjusted by means of the hand wheel *i* in the manner hereinbefore described.

Any lateral adjustment of the grinding wheels which may be required can be effected by means of a hand wheel 32 operating a screw 31 which engages with a screw thread provided in the outer end of the pin *n*. The screw 31 passes through a bridge 34 and is prevented from moving axially with relation thereto by means of collars 33. On turning the hand wheel 32 the combined carriage and holder is moved toward or away from the carrier *m*, the lateral play of the wheel *b* on the pin *c* permitting of this.

60 The grinding wheels are provided with a guard 35 secured to the framework and having a hole through its crown above each grinding wheel. Arranged above each hole is a bridge 36 having its legs attached to the guard and serving as a guide for a slide 37

connected to a screw 38 operated by means of a hand wheel and nut 39. At the lower end of the slide 37 is a dresser 40 mounted upon a pin 41 carried by the slide, so that, on turning the hand wheel and nut 39 the dresser 40 is depressed into contact with the grinding wheel.

By using a series of rollers as hereinbefore described and which form the subject matter of a separate application filed by us March 11, 1911 and serially numbered 613,790 the grinding wheels are prevented from following the surface of the rail as the rollers ride upon the tops of the corrugations of the rail and thereby permit the 80 grinding wheels to work at a regular depth.

Having now described our invention, what we claim as new and desire to secure by Letters Patent is:—

1. In rail dressing machines, a combined carriage and holder, grinding means carried thereby, means for removably pivoting said combined carriage and holder to the machine about a central longitudinal axis thereof, and additional means independent of the dressing means and of the machine for supporting said combined carriage and holder upon the rails being treated.

2. In rail dressing machines, a combined carriage holder, grinding means carried thereby, means for removably and freely pivoting the combined carriage and holder to the machine about a central longitudinal axis thereof, and a number of rollers adjacent to said grinding means, and additional means independent of the dressing means and of the machine for supporting said combined carriage and holder upon the rails being treated.

3. In rail dressing machines, a combined carriage and holder, means for removably and freely pivoting said combined carriage and holder to the machine about a central longitudinal axis thereof, grinding wheels supported upon one side of said combined carriage and holder, a number of rollers adjacent said grinding wheels, and a flanged wheel upon the other side of the combined carriage and holder.

4. In rail dressing machines, a combined carriage and holder, centrally and longitudinally arranged trunnion caps, carried thereby, vertically adjustable grinding wheels carried on one side of said combined carriage and holder, a number of rollers adjacent to said grinding wheels an adjustable flanged wheel upon the other side of the combined carriage and holder, and means for laterally adjusting said combined carriage and holder.

5. In rail dressing machines, a combined carriage and holder, vertically adjustable grinding means carried thereby, means for removably and freely pivoting the said combined carriage and holder to the machine

about a central longitudinal axis thereof means for adjusting said grinding means to the lateral plane of the rail being treated comprising a rotatable screw, a slide upon 5 said screw, a pin upon said slide, and a flanged wheel carried upon said pin, and means for laterally adjusting said combined carriage and holder.

6. In rail dressing machines, a combined 10 carriage and holder, grinding wheels carried thereby, means for removably and freely pivoting the said combined carriage and holder to the machine about a central longitudinal axis thereof, means for vertically adjusting said grinding wheels comprising a shaft carrying each grinding wheel, a bearing supporting said shaft, links extending from each bearing, a pin pivoting said links to the combined carriage and 15 holder, lugs extending from said bearing, a screw pivoted to said lugs, and a rotatable nut upon said screw, means for adjusting said grinding wheels to the lateral plane of the rails being treated, and means for laterally adjusting the combined carriage and 20 holder.

7. In rail dressing machines, a combined carriage and holder, grinding means carried thereby, means for removably and freely 25 pivoting said combined carriage and holder to the machine about a central longitudinal axis thereof, a bracket carried by said combined carriage and holder, a carrier supported upon said bracket, and a number of 30 rollers mounted upon said carrier.

8. In rail dressing machines, a combined carriage and holder, grinding means carried thereby, means for removably and freely pivoting said combined carriage and holder 40 to the machine about a central longitudinal axis thereof, and means for laterally adjusting said combined carriage and holder comprising a bracket supported thereby, a pin upon said bracket, a carrier mounted upon 45 said pin, a rotatable screw entering into said pin, and a bridge formed upon said carrier and holding said pin against axial movement.

9. In rail dressing machines, a combined 50 carriage and holder, adjustable grinding means carried thereby, means for removably and freely pivoting said combined carriage and holder to the machine about a central longitudinal axis thereof, means for supporting 55 said combined carriage and holder upon the rails being treated, means for rotating said grinding means, means for starting and stopping said driving means.

10. In rail dressing machines, a combined carriage and holder, adjustable grinding means carried thereby, means for removably and freely pivoting said combined carriage and holder to the machine about a central longitudinal axis thereof, means for starting and stopping said grinding means, means 60 for driving said grinding means comprising a shaft carrying each grinder, a universal coupling secured at one end to said shaft, an eccentrically mounted friction pinion secured to the other end of said universal coupling, a friction wheel engaging with said eccentrically mounted friction pinion, a shaft driving said friction wheel, a toothed pinion upon said shaft, a toothed wheel engaging with said toothed pinion, a shaft 65 driving said toothed wheel, a bevel wheel driving said shaft, and a bevel wheel mounted on the main driving shaft and engaging with the aforesaid bevel wheel.

11. In rail dressing machines, a combined 70 carriage and holder, adjustable grinding means carried thereby, means for removably and freely pivoting said combined carriage and holder to the machine about a central longitudinal axis thereof, means for driving 75 said grinding means, means for starting and stopping said grinding means comprising friction pinions receiving motion from main shaft and communicating said motion to the grinding means, a shaft carrying each said 80 friction pinion, a bearing eccentrically supporting said shaft, a toothed wheel secured at each end of said bearing, toothed pinions 85 engaging said toothed wheels, a shaft supporting said toothed pinions, a spiral pinion 90 on said shaft, a second spiral pinion engaging aforesaid spiral pinion, an inclined shaft driving said second spiral pinion, a bevel wheel upon said shaft, a second bevel wheel 95 engaging therewith, a shaft carrying said 100 second bevel wheel, and a hand wheel operating said shaft.
